UNITED STATES PATENT OFFICE.

JAMES P. O'BRYAN, OF HOG ISLAND, PENNSYLVANIA.

HOISTING DEVICE.

1,329,107.

Specification of Letters Patent. Patented Jan. 27, 1920.

Application filed June 14, 1919. Serial No. 304,248.

To all whom it may concern:

Be it known that I, JAMES P. O'BRYAN, a British subject, residing at Hog Island, in the county of Philadelphia and State of Pennsylvania, have invented certain new and useful Improvements in Hoisting Devices, of which the following is a specification, reference being had to the accompanying drawings.

10 This invention relates to an improved hoisting device of the differential gear and cable type, and the invention aims to provide a device of this kind particularly adapted for hoisting heavy loads, for instance, one or more tons, and which may be accomplished efficiently and in a practical manner.

15 The invention further aims to provide a hoisting device which is simple and efficient in construction, and may be manufactured for a relatively low cost and sold at a reasonable profit.

20 The invention further aims to provide a hoisting device including a casing, in which a revolute member is journaled, said member having on its periphery a plurality of cable grips, adapted to automatically grip and release the cable as the member is rotated, in combination with an improved internal reduction gearing for operating the 25 revolute member.

25 The invention further aims to provide a casing in which the hoisting mechanism is mounted, in combination with guiding means carried by the casing, for guiding the cable to and from the cable grips on the revolute member, so that the grips may more effectively grip and release the cable, as the cable engages and leaves the revolute member.

30 The invention further aims to provide a revolute member for the cable comprising a pulley casting carrying the cable grips, so that they will automatically grip and release the cable, in combination with a ring plate secured to one face of the pulley casting, so as to coöperate with the grips, to retain the cable on the revolute member, said ring plate having the marginal edge of its 35 openings provided with teeth, so that they will be engaged by the internal reduction gearing, in order to operate the revolute member, said internal reduction gearing being manually manipulated.

35 While the design and construction at present illustrated and set forth is deemed preferable, it is obvious that as a result of a

reduction of the invention to a more practical form for commercial purposes, the invention may be susceptible to changes, and the right to these changes is claimed, provided they are comprehended within the scope of what is claimed.

40 The invention comprises further features and combination of parts, as will be herein-after set forth, shown in the drawings and claimed.

45 In the drawings:

50 Figure 1 is a view in elevation of the improved hoisting device constructed in accordance with the invention.

55 Fig. 2 is a sectional view through the same.

60 Fig. 3 is a sectional view on line 3—3 of Fig. 2.

65 Fig. 4 is a sectional view through a modified construction of hoisting device, which is also constructed in accordance with the invention.

70 Fig. 5 is a sectional view on line 5—5 of Fig. 4.

75 Referring more especially to the drawings, 1 designates a casing, which may be any suitable shape or configuration, preferably as shown, though not necessarily, and may be constructed of any suitable material, such as cast metal or the like.

80 Mounted concentrically in the casing is a shaft 2 having a crank 3, and rotatable with the shaft is a gear 4. Loosely mounted on the shaft is a revolute cable engaging member 5 and which comprises a pulley casting 6, provided with a single marginal flange 7, and the ring plate 8. This ring plate has a lateral flange 9, which telescopes over the pulley casting, as shown, in order 85 to overlie the same, there being suitable screws or other means 10, for securing the ring plate to the pulley casting. The single flange 7 is so shaped on its inner portion, as to provide a fulcruming bearing for the cable grips 11.

90 These cable grips may be any suitable shape or configuration, preferably as shown, though not necessarily, and are provided with curved crotches or portions 12, to engage the fulcruming bearing on the single flange, whereby the cable grips may rock into and out of gripping engagement with the cable. In fact, certain arms of the grips or elements 11 engage recesses or cavities 13 on the inner 95

90 face of the ring plate, not only to hold the grips in place, but also to hold them from 100 105 110

creeping annularly on the pulley casting. In fact, the recesses or cavities are formed in the flange 9 of the ring plate. It will be seen that the grips or elements 11 are capable of being actuated by the cable, to retain the cable in position between the grips and the inner face of the ring plate. The other arms of the cable grips, when the first mentioned arms engage the recesses or cavities 13, partially overlie and grip the cable. The cable when allowed to feed upon and from the revoluble member engages the inner curved portions of the arms, which engage the recesses 13, so as to cause the other arms of the grips to partially overlie and grip the cable, so as to prevent the cable from slipping. The gripping devices are so mounted, that the greater the load on the cable, the greater the clamping and gripping action of the overlying arms of the grips on the cable. The marginal edge of the opening of the ring plate is provided with gear teeth 15. Mounted upon the shaft 2 is an elongated plate 16, in the ends of which pins 17 are journaled, and mounted upon the pins 17 are gears 18 and 19, which mesh with the internal teeth of the ring plate 8. It will be observed that when the crank is turned, motion will be imparted to the shaft 2, rotating the gear 4, which in turn meshes with the gears 18 and 19, imparting motion thereto, and which in turn imparts motion to the ring plate, and the pulley casting. Since the grips are actuated toward and in gripping engagement with the cable, due to the load on one end of the cable, the cable will move with the revoluble member, without slipping and thereby raise the load on the end of the cable. One end of the casing is provided with a suitable clevis hook 20, which is connected to a lug of the casing by the pin 21, whereby the hoisting device may be suspended from any suitable supporting means such as a block and tackle, or from a stationary support (not shown). The casing has a marginal flange, which is engaged by a side plate 22, which is secured in place by means of suitable screws or the like 23. A certain portion of the casing structure shown in Figs. 1, 2 and 3 is provided with guide passages 24 and 25, and a portion of the marginal flange is provided with openings 26, through which and through the passages both portions of the cable pass. By means of these openings and passages both portions of the cable are guided with relation to the casing and revoluble member, so that the cable will readily feed on and leave the revoluble member.

In Figs. 4 and 5 instead of the passages 24 and 25 and the opening 26, the outlet end of the casing for both portions of the cable is provided with guide pulleys 27, which are mounted upon the pins 28, so as to guide

the cable on and from the revoluble gripping member in the casing.

Also movable with the pin 2 is a disk 29 having ratchet teeth 30, which are engaged by a spring tensioned dog 31, so as to hold the shaft or pin 2 and the crank in different positions, and also to prevent retrogression of the revoluble gripping member in the casting. It has been found that a hoisting device of this particular kind may be used for hoisting very heavy loads, say for instance, one or more tons, and at the same time requiring but little power on the crank, for it is obvious that the crank may be operated manually, though not necessarily, for it is obvious that any other suitable mechanical operating means may be connected to the pin or shaft 2.

The invention having been set forth, what is claimed as new and useful is:

1. In a hoisting device, the combination with a casing, of a revoluble element journaled therein, said element comprising a pulley casting having an annular fulcruming bearing, a ring plate internally toothed and secured to one face of the pulley casting provided with a portion overlying the pulley casting, said portion having cavities or recesses, a plurality of cable actuated grips fulcrumed upon the bearing and having portions to enter the cavities or recesses of the overlying part of the ring plate to grip the cable against the ring plate, and means engaging the teeth of the ring plate for operating the element.

2. In a cable hoist, the combination with a casing, of a revoluble element journaled therein, said element comprising a pulley casting having a marginal fulcruming bearing, a plurality of grips engaging said bearing and being tilted on the bearing by the cable, due to the load on one end of the cable, a ring plate secured to one face of the pulley casting and having a portion opposed relatively to the grips, whereby the cable may be gripped between said portion and the grips, and means having gear connections with the ring plate.

3. In a cable hoist, the combination with a casing, of a revoluble element journaled therein, said element comprising a pulley casting having a marginal fulcruming bearing, a plurality of grips engaging said bearing and being tilted on the bearing by the cable, due to the load on one end of the cable, a ring plate secured to one face of the pulley casting and having a portion opposed relatively to the grips, whereby the cable may be gripped between said portion and the grips, and internal reduction gearing means having gear connections with the ring plate for operating the revoluble element, and means for preventing retrogression of the element.

4. In a cable hoist, the combination with

a casing, of a revoluble element journaled therein, said element comprising a pulley casting having a marginal fulcruming bearing, a plurality of grips engaging said bearing, and being tilted on the bearing by the cable, due to the load on one end of the cable, a ring plate secured to one face of the pulley casting and having a portion opposed relatively to the grips, whereby the cable may be gripped between said portion and the grips, and means having gear con-

nections with the ring plate, a certain portion of the casing having guiding means for the cable to guide the cable as it is gripped and released by the grips.
